A. S. SALAS.
PNEUMOTHERMIC APPARATUS.
APPLICATION, FILED DEC. 27, 1920.

Patented June 7, 1921.

FIG. 1.

FIG. 2.

Inventor,
Adolfo Salvador Salas,
By Henry Orlitz

Atty.

UNITED STATES PATENT OFFICE.

ADOLFO SALVADOR SALAS, OF BUENOS AIRES, ARGENTINA.

PNEUMOTHERMIC APPARATUS.

1,380,841.

Specification of Letters Patent. Patented June 7, 1921.

Application filed December 27, 1920. Serial No. 433,525.

To all whom it may concern:

Be it known that I, ADOLFO SALVADOR SALAS, a citizen of the Argentine Republic, residing at calle Maipú 671, Buenos Aires, 5 Argentina, have invented new and useful Improved Pneumothermic Apparatus, of which the following is a specification.

This invention relates to an improved pneumo-thermic apparatus, destined to close 10 an electric circuit for operating electric bells or other alarm devices, at the instant of a fire breaking out, said apparatus being adapted for use in work shops, playhouses, private buildings, stores, holds of ships and 15 the like.

As will be seen by the following description, the device operates by the expansion of the air when submitted to a sudden rise of temperature. The device may so be adjusted 20 that the sudden rise of only one degree in the temperature of the air of the room or inclosure where the same is placed, will cause the operation of the alarm device.

Such high degree of sensitiveness of the 25 apparatus, however, will not cause the operation thereof when the temperature of the air rises gradually, as when lighting a match or upon the operation of the usual lighting or heating appliances.

30 The apparatus substantially consists of a set of metallic tubes, constructed of very thin sheet metal, and communicating at their ends with chambers in turn suitably connected to oscillatory or extensible chambers 35 or plates, by means of which the slightest abrupt or sudden expansion of the air enclosed within the system, will cause the continuous operation of the device, and will simultaneously close the electric circuit of 40 the alarm device.

The invention will be better understood by reference to the accompanying drawings which illustrate the preferred embodiment of the same, and wherein:—

45 Figure 1 is an elevation, partially in central section, of a fire alarm device, constructed in accordance with my invention.

Fig. 2 shows a section of the same, along the line A—B of Fig. 1.

50 In said drawings, 1 and 2 indicate the end chambers, in communication one with the other by means of a set of tubes 3 radially conducting heat. Through the said chambers and tubes, except the central tube, extend 55 the tubes 4 through which the surrounding air may freely circulate. By this

arrangement, the concentric tubes form annular spaces and the air contained within these spaces is submitted to the influence of the surfaces of said tubes 3 and 4 for rapidly heating and cooling the thin annular columns of air therebetween. 60

The chamber 2 communicates with the extensible plates 5 arranged to contact with a screw 6, electrically insulated from the base 65 7 of the apparatus and which may conveniently be adjusted so as to predetermine the instant at which the lower plate 5 is to come into contact with the screw and thereby close an electric circuit of which the leads 8 70 and 9, leading from the respective terminals 10 and 11, are connected one to the said plates and the other to the screw 6.

The chamber 1 communicates with the extensible plates 12, of which the upper one 75 is formed with a head 13, adapted to obturate the orifice 14 of the outlet chamber 15, supported in position by an arm 16 and connected to the system by means of the tube 17. The orifice 14 may be adjusted 80 as to its outlet area by means of a screw 18, conveniently arranged in the cover 19 of the chamber 15. The arm 16 is secured to one of the standards 20 by means of a nut and screw 21, so that the height may be adjusted (by washers, shims or otherwise, not shown) for the purpose of approaching at 85 will the orifice 14 toward the obturating head 13. The standards 20 are provided with notches wherein engage the metallic 90 coils 22 which form a protective sheathing.

The space confined by the chambers, tubes and extensible plates is in communication with the outer air only by means of the controllable opening 14. 95

The operation of the device is as follows:—

The apparatus being mounted within a room, hold or any other desired space, when the air is being gradually heated as by lighting a match, lamp or the like, the air contained within the device is submitted to an expansion in relation to the outer temperature and as said expansion will be gradual, the air will escape by the orifice 14 without 100 effecting the apparatus to any large extent. 105

In case however, the rise in the temperature of the air is sudden as when a fire is breaking out, then the air contained within the device is submitted to a considerable and rapid or instantaneous expansion, owing to 110 the action of the heat transmitted thereto by

the tubes, chambers and extensible plates and as the discharge orifice 14 will not allow of the free escape of the expanded air, pressure will be generated in the interior of the device which will cause the plates 5 and 12 to extend so that the latter, assisted by the expansion of the tubes, will extend the head 13, and close the said orifice 14, owing to which the air contained in the device will 10 continue to expand and will finally cause head 5 to come into contact with the screw 6, thereby closing the electric circuit and causing the bells or other alarm devices to sound.

15 I claim:—

1. Fire alarm device, substantially comprising two air chambers in communication one with the other by means of a plurality of thin metallic tubes, concentrically 20 arranged tubes extending through some of the first mentioned tubes and allowing of the circulation therethrough of the outer air, sets of pneumatic extensible plates connected to said chamber to expand at a sudden 25 rise in the temperature outside the device, causing a sudden expansion of the air contained within the same, thereby causing one of the sets of said plates, assisted also by the expansion of the tubes, to obstruct 30 an exit orifice which constitutes the only communication with the outer air, while the other set is caused to close an electric circuit and operate a bell or other suitable alarm device, substantially as described.

35 2. In a thermostatic alarm, a hollow expansion device, a passage permitting air to enter and leave said device arranged to be opened and closed by an expansible portion of said device and means to regulate the 40 charge of said passage to vary the speed of closure of said passage by said portion.

3. In a thermostatic alarm, an expansion chamber, a passage permitting air to enter and leave said chamber arranged to be opened and closed by an expansible portion 45 of said chamber.

4. In a thermostatic alarm, an expansion chamber, a nozzle arranged opposite a wall of said chamber and to be closed by said wall upon rapid expansion of the chamber, and means to permit relative adjustment of the nozzle and wall to and from each other.

5. In a thermostatic alarm, an expansion chamber, a vent device normally venting said chamber to the atmosphere and arranged to be closed by an expansible portion of said chamber, and an electric contact closed by the expansion of said chamber caused by the expansion of the air trapped in said chamber after the closing of said 60 vent device.

6. In a thermostatic alarm, two end chambers, tubes connecting the chambers, hollow expansion plates connected to each chamber, tubes concentric with the aforesaid tubes and spaced therefrom for the passage of outside air, thereby forming annular chambers containing thin annular bodies of air subjected externally and internally to temperature changes, a venting nozzle arranged opposite the expansion plates of one chamber, a tube connecting said nozzle and a chamber, means to permit adjustment of the nozzle to and from the plates, means to adjust the area of the nozzle opening, an 70 electrical contact opposite the plates of the second chamber and a protector surrounding the above assemblage.

ADOLFO SALVADOR SALAS.
